COVER FOR VALVE-IN-HEAD MOTORS

Charles A. Wefing, Denver, Colo.

Application April 22, 1950, Serial No. 157,525

3 Claims. (Cl. 123—90)

1

This invention relates to machinery covers, and more particularly to valve covers for a valve-in-head type of automobile engine, and has as an object to provide a valve cover which silences objectionable noises such, for example, as those produced by loose adjustments of the rocker-arm assembly enclosed by the cover.

Another object of this invention is to provide a valve cover formed as a rigid unit which is not responsive to the pitch of noise produced by the mechanisms enclosed within the cover, and thereby to prevent such noises from being transmitted outside the cover.

Another object of this invention is to provide a cover for enclosing the rocker-arm assembly of a valve-in-head motor which is formed as a rigid unit responsive to a single tone, or frequency, having a higher pitch than noises produced by the mechanisms of the rocker arm assembly, whereby said produced noises cannot resound upon the cover, and the cover effectively confines said noises within the cover.

Another object of this invention is to provide a valve cover which may be easily placed upon a valve-in-head motor in conventional manner to enclose the rocker arm assembly thereon, and which has such rigidity that it will seat tightly against the motor head using only a minimum number of fastening points.

Yet another object of this invention is to provide a valve cover of the character described which is simple in construction, economical in cost, sturdy and having efficient life span equal at least to the life of the motor.

With these and other objects in view, all of which more fully hereinafter appear, my invention comprises certain new and novel constructions, combinations and arrangements of form and materials as hereinafter described and defined in the appended claims and illustrated in preferred embodiment in the accompanying drawing in which:

Figure 1 is an elevation view, somewhat diagrammatic in nature, illustrating an embodiment of the present invention as placed upon a conventional valve-in-head motor in condition for use.

Figure 2 is a section, on an enlarged scale, as taken on the indicated line 2—2 of Fig. 1 to illustrate the cover enclosing a conventional rocker-arm assembly on the head of the motor.

Figure 3 is a section as taken on the indicated line 3—3 of Fig. 2 but showing the cover only.

Figure 4 is a section, on a further enlarged scale, as taken on the indicated line 4—4 of Fig. 1,

2

illustrating the cover without the motor elements excepting for the attaching means.

Figure 5 is a bottom view of one end portion of the cover, on the same scale as Fig. 2, to show constructions otherwise not clearly illustrated.

Figure 6 is a fragmentary view, on an enlarged scale, of an attaching means as taken on the indicated line 6—6 of Fig. 1.

Figure 7 is a fragmentary view, on an enlarged scale, of a seating construction, as taken on the indicated line 7—7 of Fig. 1.

While the valve-in-head motor is an efficient type of internal combustion engine, it is objectionable to many people because of noises which occur in the rocker arm assembly of the valves on top of the motor. In the drawing there is illustrated a conventionalized motor 10 having a rocker arm assembly 11 on top of the motor,

which comprises a plurality of rocker arms 12, 20 push rods 13, and valve stems 14. Each push rod 13 is connected with one end portion of a rocker arm 12, and a valve stem 14 is connected to the other end portion. An upward movement of the push rod rotates the rocker arm 12 to depress the valve stem 14 and open the valve. Conversely, the lowering of the push rod permits the raising of stem 14 and resulting closing of the valve. In good motor adjustment there is provided a certain amount of clearance in this train of mechanisms to assure the complete closure of the valves when the push rods are at their lowered position. Such clearance must be appreciable, for the motor parts, especially the valve stems, become heated during motor operation and the expansion of the parts by heating decreases all clearances. With the proper clearances in the aforesaid elements considerable noise results from the running of the engine, and as this noise is often loud and of a knocking character, the impression is made on the untrained ear that the motor is not properly adjusted and that something is wrong. Because of this and because of the general desire of the public to have the motors of their automobiles almost completely silent, there is a tendency to adjust the rocker arm assembly of these valve-in-head motors tightly and thus eliminate noise regardless of the fact that such adjustment is inefficient and causes the valves to burn out prematurely.

The conventional valve cover which encloses the rocker arm assembly simply protects the moving parts from dirt and retains oil flowing over the assembly. Such covers are designed for no other function, and accordingly are made in a cheap manner such as by drawing or stamp-

ing a piece of sheet metal into the proper form with suitable ribs or corrugations folded therein to enhance the structural rigidity and permit the cover to be held in place with a minimum number of fastenings. No consideration is given to the tones and sound frequencies to which the cover is responsive and the corrugate rib reinforced construction makes the cover responsive to noises of many pitches as indicated by an off-tone sound of such a cover which occurs when it is struck a blow. In essence, the conventional cover acts largely as a sound box, transmitting all the motor noises to the outside and probably magnifying some noises of certain pitch.

The present invention comprises an improved cover having a tone or frequency characteristic which will not respond to frequencies of noises produced by the rocker arm assembly, effectively confining such noises within the cover and thereby silencing the motor. In attaining this improved construction several factors were determined as limitations of my construction and such factors are herein enumerated to facilitate an understanding of the invention:

(a) A cover which naturally vibrates at a frequency the same as the noise of the machinery it encloses tends to resonate and actually makes the noise sound louder.

(b) A cover formed of thin sheet material reinforced by corrugate or folded ribs to provide a plurality of flat plate-like sections in the cover, tends to vibrate at a number of different frequencies as indicated by the cover emitting a dull off-tone sound when struck by a blow, and such cover will transmit, to the outside, noises of various pitches.

(c) A cover responsive to a natural frequency less than the frequency or pitch of the noises acts somewhat as a diaphragm effectively transmitting the noises.

(d) A cover responsive only to a natural frequency higher than the frequency or pitch of the noises will not respond to the pitch of the noises and will effectively confine such noises.

By the construction and arrangement of elements as hereinafter described, my valve cover is responsive to a single high frequency tone and with such cover placed over the rocker arm assembly of a valve-in-head motor, a remarkable silencing of the motor is attained.

In the illustrated embodiment the rocker arm assembly 11 contains certain cross bars 15 which act as fastening members, and studs 16 upstanding from the cross bars 15 extend through the top of the cover 17 to provide suitable fastening means to hold the cover 17 in place. Crown nuts 18 threaded on the studs 16 conventionally secure the cover 17 in place.

At one end of the cover there is provided an opening 19 for pouring oil into the valve rocker arm assembly and for superficial inspection of the assembly. This opening is provided with conventional lugs 19' on the underside which reinforce the cover and hold a cap 20 in place, closing the opening 19.

The cover 17 is formed as a box-like open-bottom structure having the front wall 21 and rear wall 22 joining the top 23 and side walls 24. All of these walls are preferably of uniform thickness with their joining edges rounded on a fairly large radius to permit the walls and top to fair into each other in a smooth bell-like construction whereby the appearance is suggestive of an elongated bell. With such construction the cover

effectively responds to a single tone or frequency which may be easily ascertained by striking it.

It was found that a casting of aluminum was the most desirable manner of providing a light-weight cover having sufficient rigidity to respond to a natural frequency or tone higher than the frequency or pitch of the motor noises which are to be shielded. An appreciable wall thickness of the cover was found necessary to produce the high pitch tone desired, and it was found that one skilled in the art of casting metals can determine, by a process familiar to the art, a thickness sufficient to produce a given tone or pitch. Other metals than aluminum may be used, and the cover may be formed by other methods than casting. To attain a given frequency, the factors which must be considered include the wall thickness and also the density of the material and its inherent elasticity.

A plurality of regularly-spaced solid transverse ribs may be used optionally to reinforce the cover. Preferred construction may include upstanding ribs 25 on each side wall on the interior of the cover joined by transverse arches 26 across the top 23. Ribs and arches of solid and rigid construction and uniformly spaced, act as node points and thereby greatly increase the natural frequency of the cover.

In addition to the transverse ribs hereinabove described, a longitudinal rib 27 may be provided along the top 23, preferably in line with the openings therein through which the studs 16 are passed. At each opening, the rib 27 may be diverged to form a collar 28 to reinforce said opening 29. Where the elements are suitably positioned a transverse arch 26 may likewise join the collar 28 to further reinforce the structure as indicated in Fig. 5.

The openings 29 which receive therethrough the studs 16 are larger in diameter than the studs to accommodate cylindrical flanged spacers 30 through which the studs 16 are inserted. The spacers 30 are composed of rubber or rubber-like material which is not affected by chemical action of oil or by heat, their function being to provide a resilient separation layer between the cover and the studs 16 to eliminate the possibility of transmitting any high-frequency vibrations from the studs to the cover. Suitably interposed between the flanged portion of each spacer 30 and the nuts 18 on the stud 16 is a washer 31 designed to lock the nut in position and seal the opening 29 by the spacer 30.

The base of the cover is suitably formed as a flattened shelf 32 by extended feet 33 along the walls to provide the necessary increased thickness at the shelf. The feet 33 of each side may be selectively turned inwardly or outwardly as desirable to provide proper clearances for enclosed motor parts. A strip gasket 34 may seal the cover at its base, and it is preferable that the gasket 34 be of resilient or rubber-like material, or cork-like material to eliminate any tendency for high frequency vibrations within the motor block to be transmitted into the cover.

It will be seen that the structure hereinbefore described accomplishes the two functions of a rigid, tight-fitting efficient cover and a shield or confiner of the noises created by the operation of the valvehead assembly. The cast aluminum cover, which is the preferred embodiment of the present invention, has the further very useful function, namely, that it absorbs a large quantity of the motor generated heat and retains it, the

advantages thereof being obvious to motor users and those skilled in the art.

While I have described and illustrated my invention in detail, other alternatives and equivalents will occur to those skilled in the art which are within the scope of my invention, and I therefore desire that my protection be limited, not by the details of the above-described arrangements and structure, but only by the true spirit and scope of the appended claims.

I claim:

1. A method of manufacturing a cover for a rocker arm assembly of a valve-in-head motor, including walls and a top being of substantial uniform thickness and having all joining edges curved in a substantial connective radius to integrate said walls with each other and with said top, comprising ascertaining the tone of the noises produced by operation of the rocker arm assembly, casting the cover of metal with the wall and top thickness so correlated with the dimensions of the wall and the top as to provide a structure having a natural tone higher than the tone produced by the operation of the rocker arm assembly.

2. The method of manufacturing a metallic cover unit of walls and top for the rocker arm assembly of a valve-in-head motor, including ascertaining the vibratory frequency of the noises produced by the operation of the rocker arm assembly, casting the unit of metal with thickness of the walls and the top substantially uniform having their junctions curved on a substan-

tial radius to connectively integrate the walls and top into a unit adapted to respond to a single frequency vibration and correlating the dimensions of the walls and top with each other and with the metal density and elasticity to establish such single frequency at a point higher than the vibration frequency of the noises produced by the operation of the enclosed rocker arm assembly.

10 3. In the method described in claim 2, an additional step in the casting of the cover, namely, providing regularly and selectively spaced transverse ribs of the same material and integral with the body of the casting, said spacing being such as to form node points to cause said cover to vibrate at frequencies established by the spacing of said node points.
